UNITED STATES PATENT OFFICE.

PATRICK REILLY, OF BROOKLYN, NEW YORK.

STEAM-BOILER.

SPECIFICATION forming part of Letters Patent No. 359,814, dated March 22, 1887.

Application filed September 15, 1886. Serial No. 213,556. (No model.)

To all whom it may concern:

Be it known that I, PATRICK REILLY, a citizen of the United States, and a resident of Brooklyn, county of Kings, State of New York, 5 have invented certain new and useful Improvements in Steam-Boilers, of which the following is a specification.

This invention has for its object to increase the heating and steam-generating capacity of 10 steam-boilers by adding thereto a system of outside pipes arranged within the heating-space of the boiler, and so connected to the body of the boiler as to constitute a circulator for the water.

15 The invention consists of headers or upright tubes joined to the body of the boiler at its front and rear ends above and below the water-line, and a series of pipes connecting each of the front headers to one of the rear headers. These 20 said series of pipes consist of side and end pieces connected together by elbow-joints. The connections of the headers with the boiler is made by means of a system of elbow-joints, which, with the elbow-joints of the side pipes, 25 allows for unequal expansion and contraction of the various parts, and prevents all injury likely to arise therefrom; but to describe my invention more particularly I will now refer to the accompanying drawings, in which—

30 Figure 1, Sheet 1, is a side elevation of my improvements in boilers. Fig. 2, Sheet 1, is a plan view; Fig. 3, Sheet 2, a rear elevation; and Fig. 4, Sheet 2, a front elevation, the furnace-walls in all the views being shown in section.

35 The boiler *a*, to which my improvements are shown applied in the drawings, is of the return-tube cylindrical class set in brick-work, with the grate *b* at its front end, in the ordinary way. At the four corners of the brick-work of the boiler *a* are placed the headers or 40 upright tubes *c c' d d'*, which are connected together in pairs by series of side and rear pipes, the front header, *c*, to its diagonally-located rear header, *d*, by the connecting-pipes formed 45 of two parts, *e and e'*, joined together by elbow-joints *e*. The said parts *e* pass between the boiler and the other rear header, *d'*, in close proximity to the rear of the boiler. The front 50 header, *c'*, is joined to its diagonally-located header *d'* by the connecting-pipes formed of the two parts *f and f'*, fastened together by el-

bow-joints *f*, which are outside the header *d*. The parts *e* and *f* have right and left hand screw-threads, to enable them to be readily 55 placed between the elbows *e* and *f* and the headers *d* and *d'*. The front headers, *c* and *c'*, are connected at their upper and lower ends to the front head of the boiler by the pipe-connections *g* and *g'* and *h* and *h'*, respectively, 60 and they are set permanently in the front brick-work.

To enable the rear headers, *d* and *d'*, to move slightly to accommodate for variations in expansion and contraction of the side pipes, *e* 65 and *f*, and body of the boiler *a*, I join them to the rear end plate of the boiler by four-bend connections, thus providing perfect universal 70 connections therefor, the play necessary to allow for any disturbance that may occur taking place in the screw-joints of these four-bend connections.

The headers *d* and *d'* are connected to the lower part of the rear head near its center by the four-bend connections composed of the elbows *i* and *j*, fastened to the headers by nipples, the elbows *i* and *j*, fastened to *i* and *j* by the horizontal right and left hand screw-thread pipes *i*² and *j*², the elbows *i*³ and *j*³ connected to *i*² and *j*² by short pipes, and the elbows *i*⁴ 80 and *j*⁴ connected to *i*³ and *j*³ by vertical pipes *i*⁵ and *j*⁵ to the boiler by nipples. A similar arrangement of elbows and pipes, *k k' k² k³* *k⁴ k⁵* and *l l' l² l³ l⁴ l⁵*, connect the upper ends of the headers *d* and *d'* to the steam-space of the 85 boiler. Each one of the headers is provided with a blow-off cock, *m*, applied in the usual manner. By this arrangement of pipes and headers a free circulation of the water from the boiler is well provided for, and their heating 90 capacity added to that of the boiler without calling for further expenditure of fuel, and the steam generated in the pipes passes directly into the steam-space of the boiler.

Water is fed to the boiler in the usual manner. 95

Another advantage due to this system for more fully utilizing the heat generated in boiler-furnaces is that the water in the boiler is kept constantly in circulation, and the deposit of scale and mud prevented from occurring in the body of the boiler, the same taking place in the headers, the mud generally being precipitated in the rear headers, *d* and *d'*, 100

and the scale deposited in the front headers, *c* and *c'*, and the whole system may be kept perfectly clean by frequent use of the blow-off cocks *m*.

5 I do not broadly claim the combination, with a steam-boiler, of pipes connected thereto and located in the heating-space of the boiler, as I am aware that pipes and coils have heretofore been so applied to act as feed-water heaters.

10 My arrangement of pipes has no connection with the water-supply other than in providing for a circulation of the water after it has entered the boiler, and that, too, in a far more perfect manner than previous devices of similar 15 construction by reason of said pipes being connected both at their front and rear ends to the water and steam spaces of the boiler.

Instead of the pipes being connected together by screw-joints, as shown, some or all 20 of them may be joined by flange-joints.

Having now described the nature of my invention and the manner in which it is applied, what I claim, and desire to secure by Letters Patent, is—

25 1. The combination, with a steam-boiler, of an auxiliary heater and water-circulator consisting of vertical headers, each connected to the water-space and steam-space of the boiler, and a series of pipes connecting each of the 30 front headers to one of the rear headers, substantially as and for the purpose set forth.

2. In combination, a steam-boiler, four vertical headers, one located at each corner of the

boiler and connected thereto both above and below the water-line, and two series of pipes 35 arranged in the heating-space at the sides and rear of the boiler, and connected to the diagonally-located headers, substantially as and for the purpose set forth.

3. In combination, a steam-boiler, two vertical headers connected at their lower ends to the water-space and at their upper ends to the steam-space at the front end of the boiler, two series of pipes secured to these heads passing along the sides and around the rear end of the 45 boiler, two rear headers secured to the ends of each series of pipes, and four elbow-jointed connections placed between the lower ends of the rear headers and the water-space, and between the upper ends of the headers and the 50 steam-space of the boiler, substantially as and for the purpose set forth.

4. The auxiliary heater and water-circulator composed of the vertical headers *c* *c'* and *d* *d'*, the pipes *e* *e'* and *f* *f'*, front connections, 55 *g* *g'* and *h* *h'*, and the four elbow-jointed rear connections, in combination with the boiler *a*, substantially as set forth.

In witness whereof I have hereunto set my hand, at New York, county and State of New 60 York, this 14th day of September, 1886.

PATRICK REILLY.

In presence of—

ALFRED SHEDLOCK,
H. D. WILLIAMS.
